UNITED STATES PATENT OFFICE.

WILLIAM CHARLES HUNT, OF TORONTO, ONTARIO, CANADA.

PENDANT-FIXTURE.

1,264,397.

Specification of Letters Patent. Patented Apr. 30, 1918.

Application filed February 12, 1917. Serial No. 148,166.

To all whom it may concern:

Be it known that I, WILLIAM CHARLES HUNT, of the city of Toronto, in the county of York, in the Province of Ontario, in the 5 Dominion of Canada, manufacturer, have invented certain new and useful Improvements in Pendant-Fixtures, and do hereby declare that the following is a full, clear, and exact description of same.

10 This invention relates to pendant fixtures, such as those used in connection with indirect electric lighting, and has for its object to provide a form of construction, in such fixture, permitting of cheap manufacture, while being adaptable to a great variety of combination and design due to the provision of certain interchangeable co-operative parts, all of which may be suspended from the central pipe or conduit depending from the ceiling of a room, in contradistinction to the usual attaching of chains or the like, to the ceiling plate or canopy, as has generally been heretofore known, whereby the said ceiling plate or 25 canopy is free from the weight of such fixture, so that the said plate or canopy may be lowered upon the said pipe to permit inspection of the wires at the ceiling outlet, or the said plate or canopy raised without inconvenience or interference with the said pendant fixture.

The said invention consists essentially of the novel construction and arrangement of parts, whereby a plurally armed member is 35 provided adapted to be suspended centrally and a further member or members, preferably of somewhat similar design to the first mentioned member, provided to be attached to or secured in juxtaposition to the 40 said first mentioned member, but in a plane angularly disposed to and cutting the vertical plane of the said first mentioned member in more or less symmetrical manner; means being provided for securing the said 45 members in their relative positions, with respect one to another, certain of the said members being adapted to carry the supporting chains or other supporting elements carrying the reflecting bowl, or such other 50 device as may be supported by the said chains; all of which is more particularly described in and by the following specification, having reference to the accompanying drawings, in which:

55 Figure 1, is a perspective view of an orna-

mental pendant fixture, in which the said invention is incorporated.

Fig. 2, is a perspective detail view of certain of the members constituting this invention, but of a different design to those illustrated in Fig. 1, and

Figs. 3, 4, 5 and 6, are detail views of the several parts of the device illustrated in Fig. 2.

Similar characters of reference indicate 65 corresponding parts in the several figures of the drawings.

1 and 2, are plurally armed members having corresponding central disks or bosses 3 and 4 respectively, the said disks in this example being centrally orificed to permit of a bolt 5 being passed therethrough to engage with a nut 6, or other well known mechanical expedients may be adopted to effect the connecting together of the members 1 75 and 2, in Fig. 1 the nuts 6 being dispensed with.

These members are looped, or otherwise provided with means whereby they may form the support, either directly or indirectly, for the upper ends of the chains, or such other elements as may be used for the supporting of the reflecting bowl or other lower part of the fixture, and it will be seen by an examination of the Fig. 1, that a plurality of sets of these armed members may be employed for increasing the ornamental effect, in the case illustrated spindles 7 7, being employed to connect the two sets of the said members, the lower set of which is 85 reversed and carries the chains 8 8.

The upper members are centrally connected to a chain 9, in the said figure, which in turn is suitably connected to the lower end of the ceiling pipe 10, and it therefore 95 follows that no weight of the fixture is taken by the canopy 11, which may be for that reason, easily raised or lowered for inspecting purposes.

In the modified form of the invention, 100 shown in Fig. 2, the member 1 is provided with a loop 12, at its upper end, which may be adapted to be connected directly, or indirectly, with the ceiling pipe 10, the lower curved parts of the arms of the members 1 105 and 2, in this case, being preferably directly connected to the chains, or such other bowl supporting means, to provide a simple fixture.

With interchangeable members as de- 110

scribed, a great variety of designs can be produced, without necessitating the use of intricate castings, the parts being independently simple, both to manufacture and 5 to finish or polish, while when combined they give the effect of intricate work and richness of design, also permitting certain designs to be used which it would be impossible to manufacture commercially were 10 all of the arms to be integral.

This invention may be developed within the scope of the following claims without departing from the essential features of the said invention and it is desired that the 15 specification and drawings be read as being merely illustrative and not in a limiting sense, except as necessitated by the prior art.

What I claim as my invention is:

20 1. In a device of the class described, a link having a plurality of arms extending outwardly therefrom, said arms being adapted to support a pendant fixture therebeneath, a further series of similar arms 25 radiating from a common center, and means for detachably securing said last mentioned series of arms axially to said link.

2. In a device of the class described, a link adapted to be supported from above 30 and having lateral arms extending outwardly therefrom, a further link member

also having lateral arms, and being adapted to interlock with said first mentioned link member in juxtaposition thereto whereby the arms of both link members radiate from 35 an approximately common center, and means for normally securing the two link members in such interlocked relation.

3. In a device of the class described, a link member comprising a boss having 40 radial arms extending outwardly therefrom, a further link member also having a boss and radial arms, said link members being assembled together by the juxtaposition of the two bosses one above the other, 45 and locking means normally securing said bosses together.

4. In a device of the class described, a link having a pair of outwardly and oppositely extending arms in a common plane 50 therewith, a further pair of arms connected together also in a common plane, and means detachably connecting said link to said last mentioned arms, so that the plane of said last mentioned arms will cut the plane of 55 said link to produce a cruciform arrangement of said arms in combination.

Signed at the city of Toronto, in the county of York, in the Province of Ontario, in the Dominion of Canada, this 8th day of February, 1917.

WILLIAM CHARLES HUNT.
